with said ways whereby the table is guided, cross bars secured to said side bars, and bed bars secured to said cross bars.

4. The combination with a printing press comprising a main receiving table mounted for vertical adjustment, of horizontally disposed ways, an auxiliary receiving table comprising inverted channeled side bars adapted to travel on said ways, cross bars secured to said side bars, and bed bars secured to said cross bars.

5. In a structure of the class described, the combination with a main receiving table provided with means for vertical adjustment, and front, rear and side joggers, of an auxiliary receiving table comprising bed bars adapted to slide in notches in the lower edges of said front joggers, means for slidably supporting said auxiliary receiving table in a horizontal plane above said main receiving table.

6. In a structure of the class described, the combination with a main receiving table provided with means for adjustment, and front, rear and side joggers, of an auxiliary receiving table comprising bed bars, means for slidably supporting said auxiliary receiving table in a horizontal plane above said main receiving table, and means for

pivottally supporting said auxiliary receiving table in its retracted or inoperative position.

7. In a structure of the class described, the combination with a main receiving table mounted for vertical adjustment, an auxiliary receiving table slidably mounted in a plane above said main table when in its operative position, and means for removing the sheets from said auxiliary table when it is retracted to discharge them upon the main table.

8. In a printing press, the combination of a main receiving table and an auxiliary receiving table removably mounted above the main receiving table and adapted when in operative position to receive and support the sheets delivered from the press, and means for discharging the printed sheets from said auxiliary table upon said main table when the auxiliary table is retracted to inoperative position.

In witness whereof, I have hereunto set my hand and seal in the presence of two witnesses.

UNITED STATES PATENT OFFICE.

ALBERT N. SPANGELO, OF THORNHILL, MANITOBA, CANADA.

WEED AND SEED DESTROYER.

1,235,392.

Specification of Letters Patent. Patented July 31, 1917.

Application filed January 11, 1917. Serial No. 141,861.

To all whom it may concern:

Be it known that I, ALBERT N. SPANGELO, a subject of the King of England, residing at Thornhill, in the Province of Manitoba, 5 in the Dominion of Canada, have invented certain new and useful Improvements in Weed and Seed Destroyers; and I do declare the following to be a full, clear, and exact description of the invention, such as 10 will enable others skilled in the art to which it appertains to make and use the same.

My invention relates to a new machine for destroying weeds and seeds, and has for one object the provision of a comparatively 15 simple yet highly efficient machine for turning under and burying noxious weeds and seeds at such a depth as to smother the same.

With this and other objects in view, the invention resides in the novel features of 20 construction and in unique combinations of parts to be hereinafter fully described and claimed, the descriptive matter being supplemented by the accompanying drawings which constitute a part of this application 25 and in which:

Figure 1 is a top plan view of the improved machine;

Fig. 2 is a longitudinal section thereof on the plane of the line 2—2 of Fig. 1;

30 Figs. 3 and 4 are vertical transverse sections on the planes of the lines 3—3 and 4—4 of Fig. 2;

Fig. 5 is a perspective view of a fragment of the lever for adjusting one of the rock 35 shafts for raising and lowering the frame of the machine; and,

Fig. 6 is a similar view of the arched bar mounted rockably on said shaft for raising and lowering one of the plows.

40 In the drawings above briefly described, the numerals 1, 2 and 3 designate three longitudinally disposed draw bars, said bars and the connections therebetween constituting the main frame of the machine. The 45 front end of bar 1 is directed laterally and secured to bar 2 while the front end of the latter is likewise bent laterally and secured to the third draw bar 3. An oblique brace 6 extends between the bars 1 and 2 and another between 2 and 3 to impart the necessary rigidity to the frame.

An ordinary turning plow 8 is carried by the rear end of the draw bar 3 and a furrow wheel 9 is disposed in rear of said 55 plow, being carried by a vertical shaft 10 which is rockably mounted in a bearing car-

ried by a V-shaped frame 11 suitably secured to the main frame of the machine. A crank arm 12 extends laterally from shaft 10 and by means of a link 13 is connected 60 to one arm of a bell crank 14 fulcrumed on the front end of the frame. The bell crank 14 is connected with the tongue 15 by means of a suitable link 16 in a well known manner so that when said tongue is swung horizontally for turning the machine in either direction, the furrow wheel 9 will be turned to facilitate this operation.

A second plow 17 preferably in the form of a scoop is disposed in advance of and is 70 offset laterally from the plow 8, the rear end of said scoop being pivoted at 18 to the downwardly turned rear ends of the draw bars 1 and 2 while the front end of said scoop is supported by a pair of depending 75 links 19 which may be adjusted vertically by means yet to be described. A pair of bars 20 are pivoted at their front ends to the front end of scoop 17 and at their rear ends have slotted connections 21 with the 80 rear extremities of the draw bars 1 and 2 so as to limit the vertical adjustment of said scoop.

The scoop 17 delivers at its rear end into a trough 22 within which an endless belt 85 conveyer 23 of any suitable construction is mounted, said conveyer being trained around upper and lower rollers 24 as shown clearly in Fig. 2, said upper roller having a sprocket 25 driven from a sprocket chain 26 which 90 is in turn driven by means to be hereinafter described.

A transverse horizontal rock shaft 27 is mounted at the front end of the frame and extends above the draw bars 1 and 2, said 95 shaft having at one end a depending arm 28 upon which a ground wheel 29 is mounted, while a lever 30 is secured to the other end of shaft 27 for adjusting the same. A rack 31 and dog 32 are provided for locking 100 the lever 30 in adjusted position and said lever carries a rack 33 co-operating with a dog 34 for locking another lever 35 against movement. The lever 35 is either formed integrally with or otherwise joined to one 105 arm of an arched bar 36 both of whose arms are provided at their ends with bearings 37 mounted rockably on the shaft 27, it being to the inner ends of said arms that the upper ends of the links 19 are pivoted.

110 By the construction just described, operation of lever 35 will raise and lower the plow

or scoop 17 independently of the frame while rocking of shaft 27 by means of lever 30 will cause the front end of said frame to rise or lower.

5 A second transverse shaft 38 extends between the draw bars 2 and 3 in advance of shaft 27, said shaft having thereon a sprocket 39 for driving the chain 26 and a gear 40 for rotating said sprocket. A pinion 41 meshes with gear 40 and is carried fixedly by the inner end of another transverse shaft 42 disposed below shaft 38 and equipped with a ground wheel 43. Shaft 42 is rotatably carried by a U-shaped frame 44, the 10 upper ends of the arms of this frame being rockably mounted on the shaft 38 so that forward and rearward swinging of said frame will coöperate with the mechanism at the other side of the machine to raise and 15 lower the front end thereof. A lever 45 is secured to one arm of frame 44 and is provided with a dog 46 coöperating with a fixed rack 47, said lever, dog and rack serving to 20 adjust the frame 44 in the required manner 25 and to lock it in the adjusted position.

In operation, the machine is drawn across the field upon which the weeds to be destroyed are growing, the plow 8 only being lowered on the first trip across or around 30 the field. On the second trip, however, the plow or scoop 17 is lowered in addition to said plow 8, the latter now throwing the earth into the furrow previously made and thus turning the weeds and seeds under to 35 the usual extent. This is not sufficient, however, to choke or smother the seeds but a layer of subsoil is deposited on the earth thrown upwardly from the furrow, by the 40 endless belt conveyer 23, this subsoil being taken by the plow or scoop 17 from the furrow previously formed. By thus covering the weeds and seeds, they will not sprout and will thus rot and fertilize the soil. To 45 vary the depth at which the plow 8 operates, both levers 30 and 45 will be adjusted to raise or lower the frame of the machine and when it is required to vary the depth of the furrow formed by the plow 17, independent 50 adjustment of the latter may be made by operation of the lever 35.

Various changes may be made in the details of construction above described but regardless of these, the machine will be efficient and will fulfil a long felt agricultural 55 need.

I claim:

1. A weed and seed destroyer comprising

a turning plow for forming a furrow to turn the weeds and seeds under, a second plow in advance of and offset laterally from said turning plow to run in the furrow previously made by the latter, and a conveyer for carrying the subsoil rearwardly from said second plow and depositing it on the earth turned by said turning plow. 60 65

2. A weed and seed destroyer comprising a frame, a turning plow carried by said frame to turn the weeds and seeds under, a second plow in advance of and offset laterally from said turning plow, a conveyer 70 for carrying the subsoil rearwardly from said second plow and depositing it on the earth turned by said turning plow, a transverse rock shaft mounted on the front end of the frame and having a depending rigid 75 arm on which a ground wheel is mounted, an arched bar having bearings at the outer ends of its arms mounted rockably on the aforesaid shaft, links depending from the inner ends of said arms of the arched bar 80 and connected with the second plow, a lever secured to the rock shaft for adjusting the same, means for locking said lever in adjusted position, a second lever joined to the arched bar for adjusting the latter, a dog 85 carried by said second lever, and a rack co-operating with said dog and carried by the first lever.

3. A weed and seed destroyer comprising a frame, a turning plow carried by said 90 frame to turn the weeds and seeds under, a second plow in advance of and offset laterally from said turning plow, a conveyer for carrying the subsoil rearwardly from said second plow and depositing it on the 95 earth turned by said turning plow, a transverse shaft at the front end of said frame, a U-shaped frame depending from said shaft, a second transverse shaft carried rotatably by said U-shaped frame below the 100 other shaft, a ground wheel secured to said second shaft, driving connections between the two shafts, other driving connections between the upper shaft and the conveyer, and means for swinging the U-shaped frame forwardly to raise and lower the frame and for locking it in adjusted position. 105

In testimony whereof I have hereunto set my hand in the presence of two subscribing witnesses.

ALBERT N. SPANGELO.
